M. KIES.
LUBRICATING SPRING.
APPLICATION FILED NOV. 22, 1917.

Patented Mar. 26, 1918.

FIG. 5.

Mathias Kies
Inventor

By *Georg Kimmel*.

Attorney.

UNITED STATES PATENT OFFICE.

MATHIAS KIES, OF DUBUQUE, IOWA.

LUBRICATING-SPRING.

1,260,911.

Specification of Letters Patent. Patented Mar. 26, 1918.

Application filed November 22, 1917. Serial No. 203,386.

To all whom it may concern:

Be it known that I, MATHIAS KIES, a citizen of the United States, residing at Dubuque, in the county of Dubuque and State 5 of Iowa, have invented certain new and useful Improvements in Lubricating-Springs, of which the following is a specification.

This invention relates to springs and it is the dominant object of the invention to provide 10 an improved self-lubricating spring whereby the adjacent faces of the various leaves will be constantly supplied with lubricant, thereby eliminating the "squeaking" and material wear of the same, as well as 15 permitting the proper functioning thereof at all times.

Another and equally important object of the invention is to provide a spring lubricating device which will cause lubricant to 20 be uniformly supplied to the entire bearing surfaces of the same.

It is also an object of the invention to provide novel means for preventing the leaking of the lubricant over the sides of the leaves 25 of the spring, thereby avoiding any possibility of the material accumulation of dirt or grit thereon.

The invention consists, furthermore, in the novel arrangement and combination of 30 the parts of the spring, as well as in the details of the construction of the same, all of which will be more fully described in the following specification and then finally embodied in the clauses of the claim, which are 35 appended to the specification and which form an essential part of the same.

The invention is clearly illustrated in the accompanying drawings, in which:—

Figure 1 is a side elevation of the improved spring,

Fig. 2 is a detail in top plan of a fragment of one of the leaves,

Fig. 3 is a fragmental detail of the same showing one of the apertured lugs,

Fig. 4 is a similar view of a slightly modified form, and,

Fig. 5 is a side elevation of another slightly modified form.

Having more especial reference to the 50 drawings and in connection with which like reference characters will designate corresponding parts throughout the several views thereof, the numeral 1 represents the spring in its entirety, it being noted that the same 55 is composed of a plurality of semi-elliptical leaves generally indicated by the numeral 2,

which leaves, as is conventional in the art, are of different lengths.

Formed upon the marginal edges of certain of the leaves 2, namely, the upper 60 leaves, are apertured lugs 3, which lugs communicate with diagonally extending grooves 4 formed in the upper bearing faces of the spring leaves 2. In this connection, it is to be understood that any number of these 65 grooves 4 may be provided, such as conditions or preference may dictate, and further, that the same may extend in any desired direction over the bearing faces of their respective leaves. The different sets 70 of apertured lugs are adapted to be alined upon the assembling of the spring leaves 2.

In order that an efficient closure or bottom will be provided for the apertured lugs, the lower spring leaf is provided with 75 spaced solid lugs 5, these lugs being so arranged as to permit the alining of the same with the alined apertured lugs 3. Instead of being apertured, indentations or recesses 6 are formed therein and communicate with 80 oil distributing grooves similar to the grooves 4. Thus, when desiring to lubricate the spring, it is only necessary to pour lubricant into the apertured bearing lugs 3 and due to the arrangement of the lubricant 85 distributing grooves, the same will be evenly spread over the bearing faces of the various leaves.

In the Fig. 4 I have shown a slightly modified form of my invention, forming semi-circular grooves 8 about the openings in the apertured lugs 3 and about the recesses 6 in the solid lugs 5. By the provision of the semi-circular grooves, the possibility of leakage of the lubricant over the marginal 90 edges of the leaves will be lessened and consequently, the accumulation of foreign matter, such as grit or the like thereon will be prevented.

I desire to have it understood, that I may 100 form apertured lugs upon both sides of the leaves of the springs, thus insuring the proper distribution of lubricant onto the bearing faces of the same. Further, if desired, a plurality of sets of the apertured 105 and solid lugs may be employed, such as shown in the Fig. 5 and designated by the numerals 9 and 10. In this particular embodiment, it will be readily understood by persons skilled in the art that lubricant will 110 be evenly distributed over the entire bearing faces of the various leaves, notwithstanding

standing the fact that the same vary in length.

Manifestly, the construction shown is capable of considerable modification and such modification as is within the scope of my claims, I consider within the spirit of my invention.

I claim:—

1. A spring formed from a plurality of 10 leaves, sets of alined apertured lugs on some of said leaves, and solid lugs formed on the bottom leaf forming bottoms for said apertured lugs.

2. A spring formed from a plurality of

leaves, sets of alined apertured lugs on 15 some of said leaves, and solid lugs formed on the bottom leaf having recesses in the upper faces thereof and forming bottoms for the apertured lugs.

3. A spring composed of a plurality of 25 leaves having alined apertured lugs formed on certain thereof, and solid lugs formed on the bottom leaf, said leaves having oil distributing ways formed in the upper faces thereof communicating with said lugs. 25

In testimony whereof, I affix my signature hereto.

MATHIAS KIES.
